US00D711876S

(12) **United States Design Patent**
McWilliam et al.

(10) **Patent No.:** US D711,876 S
(45) **Date of Patent:** ** Aug. 26, 2014

(54) **CARD READER**

(71) Applicant: **Amazon Technologies, Inc.**, Reno, NV (US)

(72) Inventors: **Giles D. McWilliam**, San Francisco, CA (US); **Christopher Green**, San Francisco, CA (US)

(73) Assignee: **Amazon Technologies, Inc.**, Reno, NV (US)

(**) Term: **14 Years**

(21) Appl. No.: **29/472,664**

(22) Filed: **Nov. 14, 2013**

Related U.S. Application Data

(63) Continuation of application No. 29/455,402, filed on May 20, 2013, now abandoned, which is a continuation of application No. 29/433,643, filed on Oct. 2, 2012, now abandoned.
